UNITED STATES PATENT OFFICE.

GEORGE H. BARBOUR, OF PITTSBURGH, PENNSYLVANIA.

RAIL-TIE.

1,348,344.

Specification of Letters Patent.

Patented Aug. 3, 1920.

Application filed April 4, 1916. Serial No. 88,817.

To all whom it may concern:

Be it known that I, GEORGE H. BARBOUR, a citizen of the United States, residing at Pittsburgh, in the county of Allegheny and

5 State of Pennsylvania, have invented a new and useful Improvement in Rail-Ties, of which the following is a full, clear, and exact description, reference being had to the accompanying drawings, forming part of

10 this specification, in which:

Figure 1 is a view showing one of my improved ties in elevation and a track rail and joint thereon in cross-section.

Fig. 2 is a side elevation.

15 The precise nature of my invention will be best understood by reference to the accompanying drawings which will now be described, it being premised, however, that various changes may be made in the shapes 20 of the members or sections, without departing from the spirit and scope of my invention, as defined in the appended claims.

In the drawing I have illustrated one form of tie embodying my invention, and 25 which will now be described, it being premised, however, that the invention is susceptible of other embodiments.

In this drawing, the tie is shown as consisting of a central web portion 9 which is 30 bent upwardly at each edge to form longitudinal ridges having the reversely sloping surfaces 10, and which terminate in the horizontal edge portions 12. At the apex of each of the ribs 10 is an up-standing flange 35 11 whose upper portion is bent horizontally to form the rail-bearing member 12^a. The portions 12 and 12^a are preferably thicker than the other portions of the tie.

The portions 11 of the upper flanges 40 extend at right angles to the portions 12 thereof, while the similar portions 11 of the lower flanges extend at an acute angle to the portions 12 of their respective flanges, so as to form braces for the lower portions of the ties. Owing to their double seats and fastenings for the rails, together with the increased bearing on the ballast, fewer of these ties are necessary for a given length of track 45 than of the present types of ties.

50 By reason of the relatively large ballast-bearing area of my improved tie, it is possible to reduce very considerably the depth of the ballast employed, as compared with the standard depth now generally in use and 55 which is determined by well known rules, depending mainly upon the width between

the ballast-bearing faces of the ties. This not only reduces the amount of ballast material required, but the effect of reducing the ballast depth is also to lessen very materially 60 the subsidence under the action of wheel loads on the rails. It has been determined that the amount of subsidence, which is the main cause of temporary depressions or weaving action of the rails under loads, 65 varies directly as the depth of the ballast, other conditions being equal. That is to say, the greater the ballast depth, the greater the subsidence. While the cushioning action of the compressible ballast and sub-grade is highly advantageous despite the resulting deflections of the rails, excessive 70 subsidence is dangerous and its reduction is of great importance. Owing to the relatively shallow vertical section of my improved ties, it is possible to obtain a much closer spacing between the longitudinal edges of the base flanges of adjacent ties without impairing the tamping angle. In fact, with my improved tie and with any 75 given spacing between adjacent edges of the ties, the effective tamping angle is greatly increased and it is thereby possible to get the tamping implement farther under the ties. I have also shown a preferred way of 80 supporting a rail joint and rails on my improved tie. 14 designates track-rails; 15 are fish-plates secured to opposite sides of the rails, 16 are hollow rivets which secure the parts together, and 17 designates insulation such as may be employed in forming 85 an insulated joint. The rails may be secured to the ties by means of clips 13 riveted to the flanges 11 and engaging the rail base. 90

I claim:

1. A metallic rail-tie, comprising a base portion having upwardly bent portions which carry spaced apart up-standing flanges, whose upper portions are bent into substantially horizontal position to form 100 rail-bearing members, said base portion having members which extend laterally beyond said flanges to provide increased ballast-bearing surface, substantially as described.

2. A metallic rail-tie, comprising a base portion having upwardly bent portions which carry spaced apart up-standing flanges, whose upper portions are bent into substantially horizontal position to form 105 rail-bearing members, said base portion having members which extend laterally beyond said flanges to provide increased ballast- 110

bearing surface, said last-named members being of thickened metal, substantially as described.

3. A metallic rail-tie, comprising a base portion having upwardly bent portions which carry spaced apart up-standing flanges, whose upper portions are bent into substantially horizontal position to form rail-bearing members, said base portion having members which extend laterally beyond said flanges to provide increased ballast-bearing surface, said rail-bearing members being of thickened metal, substantially as described.

15 4. A metallic rail-tie, comprising a base portion formed with spaced apart up-standing flanges, whose upper portions are bent into substantially horizontal position to form rail-bearing members, said base portion having members which extend laterally beyond said flanges to provide increased bal-

last-bearing surface, said base having upwardly bent portions which carry said up-standing flanges, substantially as described.

5. A metallic rail-tie, comprising a base portion having upwardly bent portions which carry spaced-apart upstanding flanges whose upper portions are bent into substantially horizontal position to form rail-bearing members, said base portion having members which extend laterally beyond said flanges to provide increased ballast-bearing surface, at least one of said horizontally bent portions being thickened, substantially as described.

30 In testimony whereof I have hereunto set my hand.

GEORGE H. BARBOUR.
